TOWEL CABINET

Frank M. Steiner and Albert L. Overholt, Minneapolis, Minn., assignors to Steiner Sales Company, Salt Lake City, Utah, a corporation of Utah

Application March 12, 1928, Serial No. 261,151

6 Claims. (Cl. 312—38)

Towel cabinets for use in toilet or wash rooms are usually provided with a rough surfaced delivery or feed roll over which the web of clean towel is dispensed to the user. In filling or loading the cabinet with a clean towel, it is customary to stretch the clean web from the towel supply over the delivery feed roll and form a loop which depends at the front of the cabinet in position to be grasped and pulled by the user. The delivery feed roll is usually provided with a locking or control device that is manipulated by the user to obtain a suitable length of clean web for wiping purposes. When the attendant stretches the web over the feed roll to form a loop of the desired length, he finds it either necessary to raise the web out of contact with the feed roll, or if he wishes to drag the web over the roll in contact therewith, he is obliged to trip the control mechanism at intervals. This interferes with the speedy loading of the cabinet and it is not always convenient for the attendant to raise the web out of contact with the roll and hold it in its raised position while the loop is being formed, and hence the object of this invention is to provide means for temporarily rendering the lock or control device inoperative so that the feed roll will freely revolve when the web is in contact therewith and a pull is applied thereto.

A further object is to provide a means for rendering the control mechanism ineffective which is simple and inexpensive in construction and will be automatically moved to its working position when the cabinet is opened for the purpose of inserting the clean towel therein.

Other objects of the invention will appear from the following detailed description.

The invention consists generally of various constructions and combinations, all as hereinafter described, and particularly pointed out in the claims.

In the accompanying drawings forming part of this specification,

Figure 1 is a vertical sectional view through a towel cabinet embodying our invention;

Figure 2 is a front view of the same;

Figure 3 is a vertical sectional view showing the cabinet opened for loading purposes;

Figure 4 is a detailed sectional view showing the normal position of the locking or control mechanism;

Figure 5 is a detailed sectional view showing the position of the control mechanism when the key has been operated by the user to release the feed roll;

Figure 6 is a detailed sectional view showing

the door of the cabinet opened and the means in position to render the locking device temporarily ineffective;

Figure 7 is a sectional view on the line 7—7 of Figure 5;

Figure 8 is a sectional view on the line 8—8 of Figure 5;

Figure 9 is a detailed sectional view illustrating a modification of the locking device showing the normal position of the parts;

Figure 10 is a detailed sectional view of the feed roll showing the modification of Figure 9 in position to render the lock device ineffective;

Figure 11 is a sectional view on section line 11—11 of Figure 9.

In the drawings, 2 represents the side walls, 3 the rear wall, and 4 the base or bottom having suitable supporting legs 5 of a floor or stand type of cabinet.

The upper rear portion of the cabinet is preferably closed as indicated at 6.

A panel 7 also preferably closes the lower forward portion of the cabinet. Within the cabinet is a shelf or support 8 whereon a supply of clean towel 9 is placed. This shelf has a gate 10 hinged at 11 and adapted to swing forwardly and downwardly as indicated by dotted lines in Figure 1 to allow access to the space above the shelf and permit the insertion of a clean supply of towel within the cabinet.

A door 12 is hinged at 13 to the wall or panel 6 and extends downwardly and forwardly with its lower edge contiguous to the upper portion of the gate 10, and when the cabinet is in use this gate and door may be locked in their closed position by suitable means as indicated at 14 in Figure 2. This will prevent an unauthorized person from having access to the interior of the cabinet, but will allow the proper attendant to open the gate and door, or either of them, and have

access to the towel supply chamber or the delivery feed roll. Above the towel supply space or chamber we provide a delivery feed roll 15 having a roughened or frictional surface and mounted in bearings adjacent the door 12, and slightly above and in the rear of a gap or opening 16 that is preferably provided between the door 12 and the gate 10. Near the upper edge of the gate 10, we prefer to provide a rod 17 over which the web of clean towel is stretched, and from thence

over the feed roll 15 and downwardly through the gap 16 to the outside of the cabinet where it can be conveniently grasped by the towel user. As shown plainly in Figure 1, the side walls of the cabinet below the shelf 8 extend forwardly be-

yond that portion of the side walls above the shelf and provide a substantially horizontal opening 18 through which the loop of clean towel may conveniently fall into the soiled towel chamber 19 5 in the lower portion of the cabinet. A second takeup feed roll 20 is mounted in this chamber and has a sprocket belt connection 21 with the shaft of the feed roll 15 for simultaneous operation in the same direction, and above this feed 10 roll 20, guides 22 are provided in the side walls of the cabinet to receive a takeup roll 23 whereon the web of soiled towel is wound in contact by gravity with the roll 20. Arms 24 are pivoted at 25 in the cabinet and have a rod 26 between them 15 around which the web of towel passes, and forming a pull back that is raised when the web of towel is drawn forward by the user, and dropped back by gravity when the towel is released to pull the web within the cabinet. The front of the 20 cabinet also has a door 27 pivoted at 28 and adapted to swing upwardly to expose the soiled towel chamber. A stop 29 limits the inward movement of this door and a rod 30 is preferably provided at the upper end of the door for contact with the 25 towel to aid in directing it into the soiled towel chamber.

Returning now to the feed roll 15, a bolt 31 is mounted to slide transversely therein and limited in its movement by a pin 32 which projects into 30 an annular groove 33 in the bolt. This bolt normally protrudes from the feed roll a sufficient distance to enter an opening 34 provided in a stop 35 that is mounted in the wall of the cabinet and in this position the feed roll will be locked and 35 delivery of the towel prevented. A lever 36 is pivoted at 37 in the wall of the cabinet and has a finger piece 38 adapted to be engaged by the user and also has an arm 39 provided with a roller 40 in position to engage a bar 41 that is pivoted at 40 42 on the stop 35 and has an end portion 43 adapted to project into the opening 34 and engage the slide bolt 31 to move it transversely of the feed roll and disengage it from the stop 35. The normal position of these parts is indicated in 45 Figure 4 and in Figure 5 the position of the parts described is indicated when the lever 36 has been depressed by the user. The feed roll is in its release position in Figure 5 and may be turned freely to allow feed of the clean towel, and during its revolution the bolt 31 will slide by gravity 50 and return to the position shown in Figure 4 to automatically engage the stop 35 and arrest movement of the feed roll when a revolution has been completed. Obviously, in loading the cabinet 55 with clean towel, it would be awkward and inconvenient for the attendant in drawing the web of clean towel over the feed roll to form the loop, to be obliged to manipulate the release device with each revolution of the feed roll, and hence to avoid this objection and inconvenience, we provide a slide 44 that is pivotally connected at 45 to the door 12. This slide has an opening 46 normally in register with the opening 34 to allow movement of the locking bolt therein and said 60 slide also has a closed or imperforate portion 47, which, when the door 12 is moved to its open position as indicated by full lines in Figure 6, will be moved to a point directly opposite the end of the bolt 31 and in the path of the part 43 of the 65 bar 41. This imperforate section 47, engaging the end of the bolt 31 as the feed roll is revolved, will push it back into the feed roll and prevent it from engaging the stop and checking the revolution of the feed roll, and hence the attendant 70 having stretched the web of clean towel over the

feed roll after opening the door 12 and moving the slide to the position indicated in Figure 6, may freely revolve the feed roll without any attention to the lock device until a loop of clean towel web of the desired length has been formed. The attendant will then close the door 12 and in so doing, the slide 44 will be automatically returned to its release position and the lock device may then resume its usual function. The lower end of the slide is preferably provided with a slot 48 10 to receive a guiding screw 49 mounted in the lower portion of the stop 35, and serving to direct the slide vertically while permitting freedom of movement thereof. By connecting the slide to the door, it is not necessary for the attendant to exercise his memory in the least, the lock device will be automatically rendered operative when the door is closed and the open door would be too conspicuous for the attendant to forget to close it when completing the loading operation, although 15 he might neglect to render the locking device operative, if other effort on his part besides closing the door was necessary.

In Figures 9, 10 and 11 we have shown a modification in the means for rendering the locking bolt ineffective, which consists in providing a band 50 arranged to encircle the end of the feed roll and having an opening 51 through which the locking bolt is adapted to project, and also having a circumferential slot 52 to receive a pin 53 that is mounted in the surface of the roll. This band engages the surface of the roll with sufficient friction to hold it normally in position where its opening 51 registers with the end of the locking bolt, but when the bolt has 35 been retracted to the position shown in Figure 10 by the movement of the release lever 36, the attendant may grasp the band 50 and rotate it slightly as indicated in Figure 10, and thereby prevent the bolt from returning to its normal locking position, and allowing the feed roll to revolve freely. When the desired length of towel web has been formed, the attendant will return the band 50 to its normal position and when this modification is used it will be necessary for the attendant to remember to shift the position of this band, for until this is done there will be nothing to prevent the feed roll from revolving continuously when the user applies a pull to the 40 web of clean towel.

The attendant to load the cabinet, will unlock the door and gate as previously described and also open the door 27 and remove the soiled towel roll. Then placing the clean supply within the cabinet, will stretch the clean web over the feed roll 15 and draw out a sufficient length of web to form a loop of the desired length, the feed roll revolving freely to permit this operation, as the lock device has been rendered ineffective by the opening of the door 12. When the web of towel has been wound on the takeup roll with a loop of the desired length, the doors are closed and locked, and in closing the door 12, the locking device will be rendered again effective to check the feed roll at the end of each complete revolution.

We claim as our invention:

1. A towel holder having a rotary feed roll mounted therein for feeding out predetermined lengths of towel, a device movable with the roll for stopping said roll at the completion of each predetermined movement thereof and shiftable means associated with the cabinet for holding said stopping device in inoperative position to allow unlimited rotation of said feed roll.

2. A towel holder and a delivery feed roll mounted therein, over which the web of clean towel may be fed to the user, a bolt mounted to move transversely of said roll, a stop in the path 5 of said bolt, means for moving said bolt to its release position and means associated with the cabinet for holding said bolt temporarily in its release position, thereby permitting said feed roll to be operated continuously.
- 10 3. A towel holder and a feed roll mounted therein, a locking bolt transversely slidable in said feed roll, a stop in the path of said bolt to be engaged thereby for locking said feed roll against rotary movement, an oscillating bar adapted to engage and move said bolt to its release position, 15 means associated with the cabinet for operating said bar and means for temporarily preventing said bolt from engaging said stop and thus allowing continuous and uninterrupted rotation of said 20 roll.
4. A towel holder and a delivery feed roll mounted therein, having a roughened surface over which the web of clean towel is delivered to the user, a bolt mounted to move transversely of said roll, a stop in the path of said bolt, means for moving 25 said bolt to its release position, and a slide
- adapted to be moved into the path of said bolt to prevent it from engaging said stop, whereby said feed roll may be operated continuously.
5. A towel cabinet having an opening in its wall, and a door therefor, a feed roll mounted in said cabinet and over which the web of clean towel is delivered to the user, said feed roll being exposed when said door is open, a device for normally locking said feed roll against movement, a stop in the path of said locking device and means connected 10 with said door and adjusted by the movement of said door to its open position to prevent the engagement of said locking device with said stop.
6. A towel cabinet having an opening in its wall and a door therefor, a feed roll having a roughened surface over which the web of clean towel is delivered to the user, a bolt and a stop therefor normally locking said feed roll against movement, means for moving said bolt to its release 15 position for freedom of revolution of said feed roll, and a slide connected with said door and positioned by the opening of said door to prevent the engagement of said bolt with said stop.

FRANK M. STEINER. 25
